VOLATILE GAS TANK CLOSURE CAP

Charles M. Nettles, Houston, Tex., assignor to Tex-Trade,
Inc., Houston, Tex., a corporation of Texas

Application April 6, 1959, Serial No. 55,372

Term of patent 14 years

(Cl. D58—26)

Fig. 1 is a side elevational view of the volatile gas tank closure cap showing my new design;

Fig. 2 is a side elevational view of a cap taken at a 45° angle from the showing of Fig. 1;

Fig. 3 is a bottom plan view of the cap; and

Fig. 4 is a top plan view.

I claim:

The ornamental design for a volatile gas tank closure cap, as shown.
